(57) **CLAIM**

I claim the ornamental design for an LED light set, as shown and described.

DESCRIPTION

FIG. 1 is a perspective view of a LED light set showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of area '9' shown in FIG. 1;

FIG. 10 is an enlarged view of area '10' shown in FIG. 1;

FIG. 11 is an enlarged view of area '11' shown in FIG. 2;

FIG. 12 is an enlarged view of area '12' shown in FIG. 2;

and,

FIG. 13 is an enlarged view of area '13' shown in FIG. 3. The broken lines encircling a portion in FIGS. 1-3 and 9-13 are for the purpose of illustrating the boundaries of the enlarged portions shown in the views and form no part of the claim. The remaining broken lines are for the purpose of illustrating portions of the article that form no part of the claim. The LED light set is shown with a symbolic break in its length. The appearance of any portion of the article between the break lines forms no part of the claimed design.
